UNITED STATES PATENT OFFICE.

CHARLES S. WATSON, OF PHILADELPHIA, PENNSYLVANIA, ASSIGNOR OF
ONE-HALF TO ISAAC TOWNSEND, OF SAME PLACE.

FIRE-ESCAPE.

SPECIFICATION forming part of Letters Patent No. 331,746, dated December 1, 1885.

Application filed May 7, 1885. Serial No. 164,656. (No model.)

To all whom it may concern:

Be it known that I, CHARLES S. WATSON, a citizen of the United States, residing in the city and county of Philadelphia, State of Pennsylvania, have invented a new and useful Improvement in Fire-Escapes, which improvement is fully set forth in the following specification and accompanying drawing.

The figure is a side elevation of a fire-escape embodying my invention, which consists of a stock having an eye at each end, and a rope which is passed through the eyes and wound around the stock, whereby when a body strap or belt is attached to the lower eye a person may safely use the escape, the friction created preventing rapid descent of the person.

Referring to the drawing, A represents a bar or rod, which I denominate a "stock," and B represents eyes at the ends thereof.

C represents a rope, which is passed through the upper eye, then wound around the stock, and next passed through the lower eye, said rope having a hook, D, whereby it may be readily attached to a window-sill or other proper place, and when thus attached the sling, strap, or belt of the person using the escape is connected with the lower eye, and he permits himself to descend, it being seen that the eyes and stock produce friction, which prevents rapid action of the escape or running away of the same.

The extent of friction may be adjusted by properly manipulating the rope so as to increase or decrease the number of coils or windings of the rope around the stock.

Each end of the rope has a hook, D, which is constructed of a bar of metal bent so as to form an eye, having two lengths of metal and two prongs or forks spreading or flaring, and the ends thereof curved and pointed, substan-

tially as shown in the drawing, so that it may readily be fastened on the inside of the window-sill at two points, thus affording greater security to the load which may be placed on the rope, the hook and its peculiar construction possessing great strength; hence is not liable to break while in use. The reason for a hook at each end, as will be readily perceived, is that when a person has reached the ground another one in the building may hoist the rope and avoid the labor and loss of time occasioned by unwinding or uncoiling the rope from the stock, the upper hook then being released, the lower hook suitably engaged, and the proper part of the rope dropped, after which a body sling, strap, or belt is attached to the lower eye, and thus the escape may again be used, and there may be further use of the same, as is evident.

Having thus described my invention, what I claim as new, and desire to secure by Letters Patent, is—

1. A fire-escape provided with a rope having at each end thereof a hook having two flaring and pointed prongs, substantially as and for the purpose set forth.

2. A fire-escape consisting of a stock having eyes at each end thereof, and a rope having a hook at each end, each hook having an eye and double flaring points, substantially as and for the purpose set forth.

3. A fire-escape consisting of a stock having an eye at each end, and a hook formed of an eye and two prongs, the eye being of two lengths of metal bent from the prongs, substantially as and for the purpose set forth.

CHAS. S. WATSON.
